WILLIAM C. KOCH, OF CHEVIOT, OHIO

LIGHTING FIXTURE

Application filed April 28, 1932. Serial No. 608,044.

This invention relates to a lighting fixture such as a floor or table lamp.

An object of the invention is to provide a lamp with self-latching quick-action mechanical latch means whereby the lenses or panels may quickly and conveniently be released from the lamp shade frame and replaced with other lenses or panels.

Another object is to provide a lighting fixture which readily and conveniently may be altered in order to harmonize with other furnishings in a room in which the lamp is used.

A further object is to provide a lamp of the character set forth above, wherein the actuating means for releasing the lenses are normally hidden from view and disposed to preclude accidental actuation thereof, while at the same time they may conveniently be operated in the event that the lenses are to be released and replaced by other lenses.

These and other objects are attained by the means described herein and disclosed in the accompanying drawing, in which:

Fig. 1 is an elevational view of a lamp embodying the invention.

Fig. 2 is a top view taken on line 2—2 of Fig. 1.

Fig. 3 is a fragmental view taken on line 3—3 of Fig. 2, parts being broken away.

Fig. 4 is a cross sectional view taken on line 4—4 of Fig. 3.

Fig. 5 is a cross sectional view taken on line 5—5 of Fig. 3.

Fig. 6 is a plan view of a modified form of lens or panel to be used in connection with the improved shade structure.

In accordance with the present invention, the lenses or panels 8 of the lamp shade may be released from their position upon the frame 9 by merely actuating or depressing the finger piece 10 of a suitable actuating member or rod 12. One actuating member is provided for each panel, so that the user may depress the member 10 with one hand while holding the lens with the other hand upon release of the lens from the lamp shade frame. It is to be noted that the quick action mechanical latch means is constructed in such a manner that no part thereof need be bent or otherwise strained at each actuation thereof, wherefore

the latch means may be actuated an indefinite number of times without breakage or injury thereto.

The actuating member or rod 12 is reciprocably mounted upon the lamp shade frame by means of guides 13, and the triangularly shaped latch member 14 which is supported by said rod is adapted to have one corner thereof 15 normally in engagement with a notch 16 formed in the longitudinal edge 17 of the lens or panel. Upon depression of the finger piece 12 against the resistance of spring 18, the latch member 14 is moved downwardly and away from the notch 16, so as to release the panel and permit it to drop downwardly from the lamp shade frame.

As indicated in Figs. 1 and 2, the shade proper may be provided with a plurality of radial support members 19, the inner ends 20 of which are secured to a suitable hub 21 that may be mounted atop the lamp standard 22 and held in position thereon by means of a nut or other suitable fastening means 23. The outermost ends of the members 19 preferably are securely fastened to the top frame members 24 of the shade.

The lamp shade is preferably made in adjacent sections which may be suitably connected to one another for the formation of a hexagonal shade such as is illustrated in the drawing, or the sections may be of other suitable trapezium shape for the formation of other many sided shade structures.

Each of the lamp shade sections may comprise a top frame member 24, preferably of inverted U shape, a bottom frame member 25 that may be flat and straight, and a pair of opposed C-shaped members or panel guides 26 which connect the top and bottom frame members. The adjacent C-shaped members 26 preferably are maintained in spaced relationship so as to provide a channel or passageway 27 in which the latch means may be disposed. The spaced relationship of said member 26 may be maintained by means of inner and outer finishing strips 28 and 29, respectively, which are welded, soldered, or otherwise rigidly secured to the panel or lens guide member 26. In the passageway 27 are mounted suitable rod guides 13 which provide bear-

ing means for the rod 12, these guide members being fixed in position by any suitable means such as welding or soldering. The spring 18 is placed upon the rod 12 in a compressed condition, between the uppermost guide member 13 and the head of finger piece 12.

As is most clearly indicated in Figs. 3 and 4, the inclined edge 30 of latch member 14 extends through a slot or aperture 31 provided in the back 32 of the member 26, so as to render the extended corner 15 of the latch member accessible to the notch 16 with which the panel is provided (see Fig. 6).

From the foregoing it should readily be apparent that depressing of the rod 12 against the yielding resistance of spring 18 will cause the latch member 14 to move downwardly with its inclined face or edge 30 riding upon the lower edge 33 of slot 41, so as to retract the corner 15 of the latch member and remove it from engagement with the notch 16. The panel thereby is released and may be removed and replaced by a panel of different design or character. As indicated at 34, there may be provided an abutment for limiting the downward movement of rod 12 whereby to preclude complete retraction of the latch member from the slot 31. The latch rod 12 preferably is formed of resilient metal, the upper end 35 thereof being bent inwardly and upwardly of the shade frame so that the knob or finger piece 10 may be disposed interiorly of the shade, and slightly below the level of the top thereof, so as to be in a convenient yet hidden location. From the foregoing, it should readily be apparent that I have provided a very desirable means for maintaining replaceable lenses in position upon a lamp shade, said means being of a quick-acting and self-latching character so that the lenses may be positively held in position and removed and replaced an indefinite number of times without weakening the lens-holding mechanism. The self-latching means is disposed at a convenient location interiorly of the lamp shade, and between adjacent shade sections, so as to be conveniently operated and completely hidden from view when the lamp is placed in normal usage. The decorative lenses may be of parchment, celluloid, glass or other suitable translucent material in which a notch or opening such as 16 may be provided. As is clearly shown in Fig. 6, the lenses or panels may be of fabric material, screening, or other flexible material which depends upon a circumferential frame 36 for retention of its shape.

It is to be noted that actuation of the latch means not only releases the panel, but it effects also a slight but positive downward projection of the panel that overcomes any possible tendency of the panel to stick or bind within its guides. It is to be understood that various modifications and changes

in structural details of the device may be made, within the scope of the appended claims, without departing from the spirit of the invention.

What I claim is:

1. A lighting fixture having in combination a lamp shade frame and panels therefor, means on the frame for supporting the shade panels, and self-latching means adapted to operate upon application of the panels to the frame for securing the panels in position thereon.

2. A lighting fixture having in combination a series of adjacent frame sections and a notched shade panel for each section, means on the frame sections for supporting the shade panels, and spring urged self-latching means adapted normally to engage the notches and hold the panels upon application of the panels to the frame.

3. A lighting fixture having in combination a series of adjacent frame sections and a notched shade panel for each section, means on the frame sections for supporting the shade panels, and spring urged self-latching means accessible for manual actuation interiorly of the frame and adapted normally to engage the notches and hold the panels upon application of the panels to the frame.

4. A lighting fixture having in combination a series of adjacent frame sections and a shade panel for each section said shade panels each being provided with an abutment, means on the frame sections for supporting the shade panels yieldingly urged self-latching means disposed between adjacent frame sections interiorly of the frame and at the junction of the adjacent frame sections, for normally engaging the abutments of the panels and holding the panels in position upon the frame sections.

5. A lighting fixture having in combination a lamp shade frame and a supporting means therefor, translucent panels to be detachably mounted upon the frame, guides on the frame in which the panels are received and thereby maintained in a definite relationship, and self-latching quick action latch means in cooperative relationship with the frame and panels for holding the panels in position in the guides.

6. A lighting fixture having in combination a lamp shade frame constituted of adjacent sections rigidly secured together in spaced relationship to provide a way and a housing for a latching mechanism, panel guides carried by said sections, notched shade panels adapted for reception in the panel guides, a latching element disposed within the way between the sections and having an extension projectable into one of the panel guides for engaging the notch of the notched shade panel, a spring for maintaining the extension yieldingly in projected position in the panel guide, an actuating rod

reciprocably mounted for movement in the way between the sections, a free end on the rod extending from said way interiorly of the lamp shade frame, and means for retracting the extension from the projected position upon reciprocation of the rod.

7. A lighting fixture having in combination a lamp shade frame constituted of adjacent sections rigidly secured together in spaced relationship to provide a way for reception of a latching mechanism, inclined panel guides carried by said sections and top strips for holding the top ends of said panel guides in predetermined spaced relationship, shade panels adapted to be slid upwardly into said panel guides, the shade panels each being provided with an abutment at its side edge, individual latch rods supported for reciprocating movement in the ways between the adjacent shade sections, an extension on each rod said extensions being yieldingly maintained normally in projected positions so as to lie in the path of movement of the panels as they are slid into position along the guides, whereby the extensions normally engage the abutments carried by the panels, manually actuatable means extending from the latch rods to a position interiorly of the lamp shade frame and exteriorly of the ways between shade sections, whereby the rods may be manually reciprocated, and means to retract the rod extensions and release the panels upon reciprocation of the rods.

8. A lighting fixture panel for lamp shade structures which are provided with quick acting mechanical latching means, said fixture panel being constituted of a decorative sheet having upper, lower, and side edges one of said side edges having a notch formed therein for engagement with a mechanical latching means of a lamp shade structure.

9. A lighting fixture having in combination a series of adjacent frame sections and a shade panel for each section said shade panels each being provided with an abutment, means on the frame sections for supporting the shade panels, yieldingly urged self-latching means disposed between adjacent frame sections interiorly of the frame and at the junction of the adjacent frame sections, for normally engaging the abutments of the panels and holding the panels in position upon the frame sections, and means arranged to project the panels positively downwardly upon actuation of the self-latching means, for dislodging the panels from the frame sections.

10. A lighting fixture having in combination a lamp shade frame constituted of adjacent sections rigidly secured together in spaced relationship to provide a way and a housing for a latching mechanism, panel guides carried by said sections, notched shade panels adapted for reception in the panel guides, a latching element disposed within the way between the sections and having an

extension thereon projectable into one of the panel guides for engaging the notch of the notched shade panel, a spring for maintaining the extension yieldingly in projected position in the panel guide, an actuating rod reciprocably mounted for movement in the way between the sections, a free end on the rod extending from said way interiorly of the lamp shade frame, and means for retracting the extension from the projected position upon reciprocation of the rod, and means arranged to project the panels positively downwardly upon actuation of the self-latching means, for dislodging the panels from the frame sections.

In testimony whereof, I have hereunto subscribed my name this 14th day of April, 1932.

WILLIAM C. KOCH.
